TO CONTINENTAL MILLS, INC., OF PHILADELPHIA, PENNSYLVANIA

APPARATUS FOR THE PRODUCTION OF VERTICAL STRIPES ON THE CIRCULAR TYPE
KNITTING FRAME

Application filed January 24, 1930. Serial No. 423,083.

This invention relates to striping attachments for circular type knitting machines and has reference particularly to an arrangement carried by the revolving needle cylinder for working vertical stripes into the cylindrical fabric produced on such machines.

In the accompanying illustration, I have shown my improved attachment applied to a standard type of spring needle knitting machine. In Figure 1 is a side elevational view of a section of the bed and revolving needle cylinder showing a vertical striping attachment in the first step of its operation; Figure 2 is a similar view showing an advanced position of the parts and Figure 3 shows a still further advanced position of the same parts; Figure 4 is a sectional view of the needle cylinder and elevational view of the vertical striping attachment in a position corresponding to that shown in Figure 1; Figures 5 to 10 are views showing the development of a vertical stripe in the fabric during the production thereof; and Figures 11 and 12 are front elevational views of the needles and the course followed by the yarn of the fabric being knitted as well as that taken by the yarn forming the vertical stripe.

Referring to the drawings, 10 denotes the stationary bed plate of a circular type knitting machine, well known in the art. A revolving needle dial 11 is supported over the bed 10 and a trick top 12 mounted thereon, against which the needle plates 13 are adjusted to carry the spring needles 14 in their upright positions.

The needle dial 11 comprises a circular plate having a depending marginal skirt portion 15 which terminates at its lower end in a flange 16 provided with oppositely disposed beveled surfaces and downwardly directed channel pieces 17 arranged at spaced intervals about the periphery of the dial. The number and spacing of these channel pieces 17 are determined by the number and spacing of the stripes to be worked into the fabric. Each stripe worked into the fabric during the knitting thereof is produced by a similar attachment and it is

thought that it will suffice if only one is described.

Referring to the vertical striping attachment in detail, 18 denotes a vertically disposed housing formed as an integral part of the channel piece 17 and extending above and below the latter, as illustrated particularly in Figure 4. The housing 18 is provided with a channel 19 which is increased in depth from a point just below the piece 17 and extends to the top of the housing. The housing 18 is anchored in upright position on the beveled surface of the flange 16 by means of a pair of U-shaped clamps 20, one thereof being disposed on opposite sides of the housing and bearing against the beveled edge at its upper end and against the lower end of the piece 17 at its other end, the clamping action being brought about by a clamp screw 21 mounted in the clamp 20 and screwed into the upper portion of the channel piece 17. The inner arm of the piece 17 in each instance, is inclined slightly inwardly towards the center of the cylinder and carries an angular bracket 22 for the purpose of supporting an individual bobbin 23. The bobbin 23 has its axis disposed at an angle directed upwardly and radially of the cylinder so that during operation the yarn A, which is the yarn from which the vertical stripe is worked, may be readily withdrawn, as illustratively exemplified in Figure 4.

Slidably mounted in the channel 19 of the housing 18 is slide bar 24 which is loosely held in its channel by means of two face plates or strips 25 which project over the channel along its opposite upright side edges and overlie the marginal portions of the slide bar 24, as illustrated in Figures 1, 2 and 3. The slide bar 24 comprises a flat straight strip of cold rolled steel having its inner face cut away to form a channel 26 corresponding with the deeper portion of the channel 19 for the purpose hereinafter described. The opposite or outer face of the slide bar 24 is provided with a very shallow groove 27 which extends from the lower end of the bar 24 to a point substantially two-thirds the height of the latter. Just above the upper end of the

groove 27 the bar 24 is provided with an inclined slot 28, which, looking into the front face of the attachment, projects downwardly from left to right and within the space between the inner side edges of the face pieces 5 or strips 25. The slot 28 runs through the bar 24, and opens into the groove or channel 26. A plate 29 is adjustably mounted in the shallow groove 27 on a screw 30, which screws into a tapped opening in the bar 24 just below the lower end of the channel 26 and which projects through a slot 31 in the plate 29. The upper end of the plate 29 is provided with a transversely disposed beveled edge 32 capable of adjustment over the slot 31 to cut off any portion of its lower end. Adjacent the lower end of the bar 24, the latter carries a cam follower 33 in the form of a pin with a central flange 34 cut away on opposite sides 10 to permit passage thereof between the face strips 25.

Slidably mounted in the upright bore formed by the channels 19 and 26 is an axially and rotary movable spindle 35, which carries 25 a radially disposed pin 36 at a point short of its lower end to project through the inclined slot 28. The lower end of the spindle 35 is provided with an axially disposed groove 36' in which a spring finger 37 is housed for the 30 purpose of providing frictional resistance against the housing 18 when the spindle 35 is moved up or down. The upper end of the spindle 35 is provided with a yoke 38 and longitudinal spring groove 39. A stud pin 35 40 is mounted at its ends in the yoke 38 and supports a yarn guide 41, which is urged to swing in the direction of the adjacent needles 14 by means of a spring 42 mounted in the 45 spring groove 39.

40 The yarn guide 41 is a bell crank shaped member, the shorter arm 41' of which projects outwardly away from the needle ring, while the longer arm 43 projects directly into the 45 needle ring. The end of the arm 41' is provided with an eye 44 through which the yarn 50 A is threaded and passes to a cylindrical eye 45 at the extreme upper end of the arm 43. The wall of the eye 45 is tapered to a reduced diameter at its outer end so as to be introduced into the space between adjacent needles 14 in the operation of the device. The yarn guide 41 is swung outwardly against the tension of its spring 42 by means of cam surface 55 46 cut in the face of the upper end of the needle plate 13 disposed directly in back of the attachment. The cam surface 46 comprises a beveled surface projecting from a point adjacent the inner plane of the plate 60 13 outwardly in a gentle slant to the face of the plate on a line just above the upper end of the housing 18, so that as the yarn guide 41 descends to complete its operation, the end of the arm 43 beneath the eye 45 is 65 brought into contact with the upper end of

the cam 46 and is rocked outwardly away from the plane of the needles.

The yarn A feeding to the eye 44 comes from the bobbin 23 and first passes through a tensioning member 47 projecting outwardly from the right side of the housing 18 and then through a take up eye 48. The eye 48 is a cylindrical element carried at the end of an arm 49 which is pivotally mounted on a pin 50 at the back of the housing 18 adjacent its lower end, and which is urged to normally swing outwardly away from the tensioning element by means of a coiled spring 51 disposed about the pin 50 to which it is attached at its outer end while its other end is anchored in the arm itself. When the yarn A is under tension as the guide travels upwardly the arm 49 is raised until the eye 48 aligns with the tensioning device, a position which releases the yarn from the latter while the necessary amount is drawn forward. The yarn guide 41 during its movement to low position, illustrated in Figures 1 and 4, carries the yarn with it and the slack in the latter is taken up by the outward movement of the arm 49 under tension of its spring 51. No additional yarn will be drawn from the bobbin 23 during outward movement of the arm because of grip maintained on the yarn A by the tensioning device 47.

Reciprocal movement is imparted to the slide bar 24, during its peripheral movement with the cylinder past a certain point, by means of a cam 52, which comprises an L-shaped standard 53 mounted, with its longer arm in upright position, on the bed plate 10 and supported on the upright arm is a triangular plate 54, arranged so as to bring its base parallel with the bed 10, while the inclined sides are directed upwardly and are disposed in the path of the cam follower 33. Disposed over the plate 54 and following the downward slope thereof is a second plate 55 which forms a cam slot 56 with the first plate 54 whereby the follower 33 in its circular travel after being raised along the rise in the plate 54 is engaged in the cam slot 56 and caused to move downward again to its initial position.

It will be understood that the yarns A may be introduced into the knitted fabric for every row knitted by merely utilizing one knitting attachment or by following each attachment with a cam arrangement 52. In the present instance, however, it will be assumed that at least four knitted rows are built up before the vertical stripe yarn A is brought into position to become effective.

The operation of the attachment to introduce the vertical stripe into the fabric being knitted, will be described in connection with Figures 5 to 12. It will be assumed that the circle of needles 14 is traveling in a clockwise direction when viewed from the top and the individual needles 14 before

which the vertical striping attachment is mounted are approaching a station where a new row is to be started. The beards of the needles 14 are carrying the stitches of the 5 last row, as shown in Figures 5 and 11, and the vertical stripe yarn A has been following down in front of the four rows of stitches and between the channel in the knitted fabric corresponding to the space between two adjacent needles. The yarn guide 41 is in the 10 position shown in Figures 1 and 5, that is, it is swung to the right and the pin 36 is at the upper end of the slot 28, see Figures 1 and 4, while the cylindrical eye 45 is bearing 15 on the cam surface 46 in the needle plate 13. As the cam follower 33 engages the rise in the cam 52, the slide bar 24 is caused to move upwardly in an axial direction and its first movement is axially of the spindle 35, which 20 is yieldably held by its spring connection 37, and which, therefore, is rotated to move the guide 41 from right to left as the pin 36 moves through the slot 28. Subsequent upward movement of the slide bar 24 is followed 25 by the spindle 35 which is carrying the yarn A upwardly on the left side of the needle 14 to the position illustratively exemplified in Figures 2 and 6. It should be kept in mind at this stage in the operation that as 30 the guide 41 rides off of the cam surface 46, the eye 45 swings inwardly between the needles 14. Therefore, as the eye 45 rides upwardly, the yarn is carried under the beard of the needle to a point above the latter. 35 At this stage in the operation the follower is a peak of the cam.

Continued movement of the cylinder 11 carries the follower 33 into the cam slot 56 and starts the slide bar 24 downward. The 40 initial step in this movement is to cause the spindle 35 to swing around in back of the needle before moving downwardly with the slide bar 24. This is accomplished by movement of the pin 36 in the slot 28 from the low 45 end to the high end, as the spring 37 again exerts a yielding pressure to hold the spindle elevated while the slide bar is descending. This position is shown in Figures 3, 7 and 12. As previously described, the slack in the yarn A is taken up as the spindle descends by the 50 arm 49.

Thus far the operations of the device have brought the yarn A around the needle 14 to the position shown in Figure 7 and the first 55 position of Figure 12. At this point a new stitch B' is being introduced in the usual manner while the old stitch B is pushed to the lower portion of the needle as shown in the second position of Figure 12. The lowering of the stitch is caused by a shoe 57, shown in dotted lines in the different positions of Figure 12, which is regular equipment with this type of machine. The new stitch B' catches under the beards of the passing needles, as shown in Figure 9. The beards are

then closed over the new stitches and old 70 stitches B ride upwardly carrying the loop in the yarn A over the beard to the position shown in Figure 10 and the last position of Figure 12.

The needles 14 and cylinder 11 continue to travel and as previously stated a number of rows of stitches are introduced before the same vertical stripe attachment again engages the cam 52. In the meantime the yarn A from the last loop merely follows down 75 behind the stitches until it is again required to form the next loop.

If the number of needles is to be increased, it follows that they will be closer together and the movement of the yarn guide 41 must necessarily be much less. Adjustment of the plate 29 is made to reduce the effective length of the slot so that axial movement of the slide bar will be shorter before picking up the spindle 85 35 and yarn guide 41.

Having now described our invention, what we claim and desire to secure by Letters Patent is:

1. In a circular spring needle knitting machine having a revolving needle cylinder and upright bearded needles therefor, the combination of an attachment to work a yarn into vertical stripe in the fabric being knitted, comprising a yarn guide and means for moving the guide in a rotary direction to carry the yarn across a needle, then upwardly to bring the yarn under the beard of the needle and then around the back of the needle and down the other side to form a loop above the last stitch of the fabric being still on the needle, so as to enable the loop to be stripped from the needle with the stitch. 90

2. A knitting machine, as claimed in claim 1, in which said yarn guide comprises a pivotally mounted member having an eye 95 through which the yarn is guided about the needle. 105

3. A knitting machine, as claimed in claim 1, in which said yarn guide comprises a pivotally mounted bell crank member, the ends of the arms thereof being provided with eyes for guiding the yarn, said means for moving the guide comprising a spindle mounted for rotary and axial movement and having the bell crank member pivotally mounted on its upper end. 110

4. A knitting machine, as claimed in claim 1, in which said yard guide comprises a pivotally mounted bell crank member having the 120 ends of the arms thereof provided with eyes to receive the yarn therethrough, said means for moving the guide comprising an upright spindle mounted for rotary and axial movement and having the bell crank member pivotally mounted on its upper end, a housing and a slide bar therefor, the housing being carried by the revolving needle cylinder, said housing and slide bar being provided with grooves adapted to form a bore to receive the said 125 130

- spindle, and means for first imparting rotary movement to the spindle from the axial movement of said slide bar before moving axially with the slide.
5. In a knitting machine of the circular spring needle type, the combination of an attachment for working a vertical stripe in a fabric being produced, comprising a housing attached to the rotary needle cylinder of
- 10 the machine, a cam stationary on the knitting machine, and a yarn guide operated from the cam and supported in said housing for movement in a rotary and axial direction to carry the yarn in a loop about a needle.
- 15 6. An attachment for working a vertical stripe in a fabric as claimed in claim 5, in which the yarn guide comprises a bell crank member having eye openings at the ends of the arms, a spindle carrying the member at its
- 20 upper end, a slide bar having an inclined slot and a recess to receive a portion of the spindle, said housing having another recess to receive the other portion of the spindle, a pin carried by the spindle and projecting through
- 25 the slot in the bar, and a cam follower on the lower end of the slide bar to engage the said cam, whereby the slide is raised to rotate the spindle and move it axially and then in a rotary and axial movement again to return
- 30 the guide after the loop or yarn has been formed about the needle.
7. An attachment for a rotary knitting machine as claimed in claim 5, in which the cam comprises a triangular shaped plate and a
- 35 second plate spaced from the downwardly inclined side of the first plate to form a cam slot, and means mounted in the housing and carrying the yarn guide and disposed to engage the cam to reciprocate the guide.
- 40 8. An attachment for a circular spring needle knitting machine, as claimed in claim 5, in which the yarn guide comprises a bell crank member having eye openings at the ends of its arms, a spindle at the end of
- 45 which the bell crank member is pivotally mounted, a slide bar for the housing and having a recess coinciding with a recess in the housing to form a bore for the spindle, a spring in the spindle yieldably attaching the
- 50 latter to the housing, said bar having an inclined slot and a pin operating therein carried by the spindle to cause the latter to receive rotary movement from the axial movement of the bar in either direction, a follower at the
- 55 lower end of the slide bar, and a stationary cam disposed in the path of the follower during a portion of the rotary movement of the needle cylinder to reciprocate the slide bar.
9. An attachment for working a vertical
- 60 stripe in a knitted fabric, as claimed in claim 5 including means for supporting a yarn bobbin to move with the attachment, and means for tensioning the yarn and taking up slack therein between the bobbin and the yarn
- 65 guide.
10. An attachment for working a vertical stripe in a knitted fabric, as claimed in claim 5, including a yarn bobbin support for the attachment, a tensioning device mounted on said housing to receive the yarn passing from the bobbin, and a yarn take-up between the tensioning device and the yarn guide.
11. An attachment for working a vertical stripe in a knitted fabric being produced on a circular spring needle knitting machine in which a needle plate mounted on the rotary needle cylinder is provided with a cam surface, and the attachment comprises a pivotally mounted yarn guide for carrying the yarn in a loop about a needle during a rotary and axial movement of the guide, said guide being brought into contact with the cam surface of said needle plate to take it out of the space between two adjacent needles, and means for yieldably moving said yarn guide about its pivot in the direction of said cam surface.
